UNITED STATES PATENT OFFICE

111,006

DESIGN FOR A RANGE

Jacob Teller, Chicago, Ill., and Arthur P. Schulz,
Michigan City, Ind., assignors to G. & J. Teller,
Chicago, Ill., a partnership composed of Grace
Teller and Jacob Teller

Application January 6, 1938, Serial No. 74,118

Term of patent 14 years

To all whom it may concern:

Be it known that we, Jacob Teller and Arthur P. Schulz, both citizens of the United States and residents of Chicago, in the county of Cook and State of Illinois, and Michigan City, in the county of La Porte and State of Indiana, respectively, have invented a new, original, and ornamental Design for a Range, of which the following is a specification, reference being had to the accompanying drawing, forming a part thereof.

Figure 2 is a similar view thereof on a slightly smaller scale with a portion of the top in raised position and with the burner panel and front door panels in open positions.

The side of the range not shown in each of the figures of the drawing is similar to the side shown.

We claim:

The ornamental design for a range, as shown and described.
